Primary Examiner — Paula Allen Greene*(74) Attorney, Agent, or Firm* — Michael Best and
Friedrich LLP**(57) CLAIM**The ornamental design for a headphone as shown and
described.**DESCRIPTION**FIG. 1 is a perspective view of a headphone showing our
new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a cross sectional view thereof cut along the line 8-8
of FIG. 2;FIG. 9 is a cross sectional view thereof cut along the line 9-9
of FIG. 2; and,FIG. 10 is a reference perspective view thereof wherein the
left and right housings of the headphone are each in alternate
positions.**1 Claim, 7 Drawing Sheets**| (56)	References Cited
